United States Patent Office

Des. 213,150
Patented Jan. 7, 1969

213,150

DISPLAY STAND

Francis W. McBain, 3605 Riverside Drive,
Crystal Lake, Ill. 60014

Filed Nov. 22, 1967, Ser. No. 9,514

Term of patent 14 years

U.S. Cl. D80—9
Int. Cl. D20—02

FIG. 1

FIG. 2

FIG. 3

FIG. 1 is a perspective view of a display stand embodying my new design.

FIG. 2 is a side elevational view thereof.

FIG. 3 is a top plan view thereof.

The broken line representation of a displayed article in FIG. 2 is for purposes of illustration only.

I claim:

The ornamental design for a display stand, as shown and described.
